UNITED STATES PATENT OFFICE.

MANLEY J. CHAPLIN, OF SEATTLE, WASHINGTON, ASSIGNOR OF ONE-HALF
TO HERMAN RUTSCHOW, OF SEATTLE, WASHINGTON.

TAP FOR BEER-BARRELS.

SPECIFICATION forming part of Letters Patent No. 729,545, dated June 2, 1903.

Application filed January 7, 1903. Serial No. 138,115. (No model.)

To all whom it may concern:

Be it known that I, MANLEY J. CHAPLIN, a citizen of the United States, residing at Seattle, in the county of King and State of Washington, have invented certain new and useful Improvements in Taps for Beer-Barrels, of which the following is a specification, reference being had therein to the accompanying drawings.

10 This invention has relation to improvements in beer-barrel taps; and it consists in the construction, novel arrangement, and adaptation of devices, as will be hereinafter more fully described and claimed.

15 The object of the invention is the perfection of a tap for use on or with any beer-barrel. This object I accomplish by the means shown and illustrated in the accompanying drawings, in which—

20 Figure 1 is a central longitudinal section through a barrel-tap embodying my invention. Fig. 2 is a similar view of the socket shown in Fig. 1 with the bung-stopper in place. Fig. 3 is a view of Fig. 2, taken in 25 the direction indicated by arrows y. Fig. 4 is a perspective view of part of the draw-tube casing.

25 Referring to the said drawings, the letter A represents a bung-socket having an external screw-thread, as shown at a, for securing the same in the bulge or head H of the beer barrel or cask to which the invention is applied. The socket is provided at one end with a contracted cylindrical opening b, for the reception of a cork stopper s, and terminating in peripheral shoulder b'. The other end of the socket is formed with oppositely-arranged longitudinal slots C, which terminate interiorly of the socket in transverse oblique shelves c.

30 D indicates a chambered casing, preferably made of two parts d and d', integrally coupled by screw-threads e and a set-screw e'. Adjacent to one end of the casing part d' are laterally-projecting studs f, adapted to be entered into the aforesaid slots.

35 g is a circular offset, having at its periphery a downwardly-extending flange g' to provide an annular cavity h to receive a washer W. 40 d'' denotes a boss integral with the outer part d of the casing, in which is screwed a

nipple i for making connection by a flexible pipe with the usual air-supply pump.

T is a cylindrical draw-tube, which is connected in any suitable manner with a faucet 55 and is externally of less diameter than the said contracted opening of the socket and also the reduced opening k of the casing.

Under the last-named opening is a shoulder k', against which is placed a packing ring or 60 washer L for making a tight joint around the draw-tube. Internally of the casing is a sleeve M of greater internal diameter than is the said draw-tube and of a length greater than the distance between the socket-shoulder b' and the face l of the washer L when the casing-studs f have engaged the said shelves c.

N is a belt-channel surrounding the said sleeve opposite to the air-inlet opening of boss 70 d'', to which communication is made with the inside of the sleeve by apertures n, whereby air is admitted to the barrel.

The operation of the invention will now be described, reference being made to Fig. 1. 75 The socket being supposed to be inserted in the bung-hole and closed by a stopper, (shown by broken lines,) the casing containing the afore-described sleeve and washers W and L is entered into the socket by passing the projecting studs f through the slots thereof and upon being partially rotated is caught by studs, and the said washers are slightly compressed. The draw-tube is now inserted 80 through the casing and its sleeve, dislodging the said stopper, and when in the required position the casing is rotated until stopped by one of the said studs being intercepted in its travel by a lug x, during which turning the casing is obviously drawn into the 85 socket, further compressing the washer W and through the interposition of the sleeve the other washer, L, thus not only making non-leakable joints thereat, but also locking the draw-tube in its set position by the compressive force of the last-mentioned washer. 90

Having described my invention, what I claim as new, and desire to secure by Letters Patent, is—

1. The herein-described device, comprising 100 in combination with a draw-tube, of a bung-socket having an external screw and having

2

an opening extending therethrough which is reduced at one end and terminates at a shoulder b' intermediate said opening, oppositely-arranged longitudinal slots at the other end 5 of socket terminating in oblique shelves internal of the socket, a casing having external projecting studs adapted to be entered said slots and provided with a cylindrical chamber having a shoulder k' at its outer end, an 10 external off-set cavity h surrounding said casing, a perforated sleeve of greater internal diameter than the said tube and extending from the shoulder b' of the socket to within a short distance of the chamber end k' of the 15 casing, and communicative connection between the said perforations of the sleeve and a source of air-supply, substantially as and for the purposes set forth.

2. In a device of the character set forth, the 20 combination with a draw-tube, a bung-socket provided with an internal shoulder intermediate its length, a casing adapted to be entered said socket and means for drawing the same into and engaging with the said socket 25 by rotating the casing, and communicative connection between the inside of said casing and the source of air-supply; of an annular washer external of and carried by the casing

and adapted to bear against the said socket, a washer positioned at the outer end of the 30 chamber of the casing, and a sleeve extending from outside the inner end of the casing to the last-named washer, whereby it is compressed simultaneously with the other washer and the coupling of the casing with socket, 35 substantially as described.

3. In a device of the character described, the combination with the socket, a chambered casing provided with an air-inlet, a draw-tube extending axially through said casing 40 and said socket; of a perforated sleeve surrounding said tube so as to provide an annular passage therebetween the entire length of the sleeve, said sleeve extending from outside the inner end of the casing to within a short 45 distance from the shoulder at the outer end of the chamber of said casing, and communication between said passage and the said air-inlet of the casing, substantially as described.

In testimony whereof I affix my signature 50 in presence of two witnesses.

MANLEY J. CHAPLIN.
